UNITED STATES PATENT OFFICE.

SARAH ROBINSON, OF WELCH, WEST VIRGINIA, ASSIGNOR OF ONE-FOURTH TO
RICHARD B. ANDERSON, OF ALGONQUIN, WEST VIRGINIA.

WASHBOARD.

Application filed October 18, 1921. Serial No. 508,449.

To all whom it may concern:

Be it known that I, SARAH ROBINSON, a citizen of the United States, residing at Welch, in the county of McDowell and State 5 of West Virginia, have invented new and useful Improvements in Washboards, of which the following is a specification.

The object of my said invention is the provision of a washboard comprising a 10 roughened member adapted to be readily removed from the frame when worn, and as readily replaced with a new roughened member, together with simple, compact and efficient means for positively securing said 15 member in working position in the frame so that there is no liability of the roughened member being casually displaced incident to the use of the washboard, and yet when desired or necessary the roughened member 20 may be readily released for removal and when a new roughened member is placed in the frame the new member may be expeditiously and positively locked in position.

Manifestly when the roughened member 25 is rendered useless through wear, the frame is saved and may therefore, be used in succession with a number of roughened members.

To the attainment of the foregoing, the 30 invention consists in the improvement as hereinafter described and definitely claimed.

In the accompanying drawings, forming part of this specification:—

Figure 1 is a front elevation of my novel 35 washboard, with parts in section.

Figure 2 is a cross section of the same on the line 2—2 of Figure 1.

Figure 3 is an enlarged perspective of the locking bar per se.

Figure 4 is an enlarged detail section 40 taken on the line 4—4 of Figure 1.

Figure 5 is an enlarged detail section taken in the same plane as Figure 2.

Similar numerals of reference designate 45 corresponding parts in all of the views of the drawings.

The roughened member 1 of my improvement is of plate-like form, and is ribbed or otherwise roughened as indicated by 2. On 50 one of its edges the said member 1 is provided with a handle 3 to facilitate its manipulation, and at 4 it is provided with one-half of a groove of dovetail form in cross section, see Figures 2 and 5. The said 55 groove portion 4 extends throughout the

height of the member 1 at a point adjacent to the handle-bearing edge of the member as will be understood by comparison of Figures 1, 2 and 5.

The said roughened member 1 is removably sheathed in a receptacle 5 in the frame 6, the said receptacle being open at the front side and at one end and being defined by the back wall 7, one side bar 8 and the upper and lower cross bars 9 and 10 of the frame. 60 It will also be noted that flanges 11 are provided on the upper and lower cross bars 9 and 10 so as to prevent the roughened member 1 from casually moving forwardly from the receptacle 5. Flanges 11^a for the same 70 purpose are also provided on the side bars of the frame. In the side bar 12 of the frame is provided a groove and a groove portion for cooperation with the groove portion 4 in the roughened member 1 and the locking 75 bar 13. From the upper end of the said side bar 12 to the upper end of the receptacle 5 the groove in the side bar 12 is of complete dovetail form in cross section, the latter groove portion being designated by 14 in Figure 4, and from the lower end of the receptacle 5 to the lower closed end of the groove, the groove is of complete dovetail form in cross section, the latter groove portion being designated by 15 in Figure 1. From a point opposite the upper 80 end of the receptacle 5 to a point opposite the lower end of the said receptacle 5 the portion of the groove in the side bar 12 is of partial dovetail form in cross section as designated by 16 in Figure 5. The locking 85 bar 13 is of dovetail form in cross section and is provided at 17 with a handle for its convenient manipulation. Manifestly when the said locking bar 13 is in a position shown in Figures 1 and 2, the roughened member 1 90 will be securely locked in the frame. When, however, it is desired to remove the roughened member 1 it is simply necessary to withdraw the locking bar 13 upwardly out of the frame and out of the member 1 when 100 the said member 1 may be withdrawn endwise from the frame. A new roughened member 1 may then be introduced endwise into the receptacle 5 of the frame 1, and when said member 1 is completely inserted, 105 it is simply necessary to replace the locking bar 13 in engagement with the frame and roughened member 1 when the new roughened member will be securely locked in position.

110

It will be apparent from the foregoing that the frame and the locking bar of my improvement are adapted to be used in conjunction with a plurality of roughened members 1 in succession, so that when a roughened member 1 is impaired by wear, the frame and the locking bar 13 are not rendered useless. On the other hand when a roughened member 1 is rendered useless through wear, 10 the said roughened member 1 alone need be discarded, which obviously contributes to economy in practice.

It will also be apparent from the foregoing that notwithstanding the facility with 15 which the locking bar 13 may be introduced and removed, the said bar 13 is highly efficient in positively securing the removable roughened member 1 in the frame, and is so arranged relatively to both frame and 20 roughened member that the washboard as a whole is not rendered cumbersome.

I have entered into a detailed description of the construction and relative arrangement of parts embraced in the present and preferred embodiment of my invention in order 25 to impart a full, clear, and exact understanding of said embodiment. I do not de-

sire, however, to be understood as confining myself to the said specific construction and relative arrangement of parts inasmuch as 30 in the future practice of the invention various changes and modifications may be made such as fall within the scope of my invention as defined in my appended claim.

Having described my invention, what I 35 claim and desire to secure by Letters Patent, it:—

In a washboard, the combination with a frame having a receptacle open at one side edge of the frame and also having a groove 40 extending lengthwise of the frame adjacent to said side edge, a roughened member removable edgewise from the receptacle of the frame and having a lengthwise groove to register and cooperate with that in the 45 frame, and a locking bar arranged lengthwise of the washboard removably sheathed in the said grooves of the frame and roughened member to positively secure the latter in the receptacle of the former. 50

In testimony whereof, I affix my signature.

SARAH ROBINSON.
